CAST METAL WINDOW FRAME

Filed Oct. 17, 1929

INVENTOR:
CHARLES GABRIEL OHARA,
BY *Arthur E. Paige,*
Attorney.

UNITED STATES PATENT OFFICE

CHARLES GABRIEL O'HARA, OF NORRISTOWN, PENNSYLVANIA

CAST-METAL WINDOW FRAME

Application filed October 17, 1929. Serial No. 400,173.

My invention may be employed with particular advantage in what are known as casement structures and particularly for cellar windows, and as hereinafter described my invention is adapted to be used in either frame, brick, or other masonry buildings.

It is the object and effect of my invention to provide a window frame formed of four primarily separate members of such construction and arrangement that each may be cast of suitable metal, such as iron, and assembled in rigid relation with each other to produce a frame at less cost than an ordinary wooden frame of the same size.

15 Of course, numerous attempts have been made to produce window frames of cast metal but the construction and arrangement thereof have been such as to necessitate machining or other costly facing operations at the 20 regions thereof which must be brought together to form joints between the several members thereof. Therefore, an object and effect of my invention is to provide a cast metal frame so constructed and arranged that 25 it is unnecessary to machine or otherwise face the portions thereof at the joints. Moreover, a considerable item of cost of such structures of the prior art is incident to the provision of hinge members and fastening means.

30 Therefore, a further object and effect of my invention is to so construct and arrange one of my improved cast frame members that sash hinge elements may be provided thereon of tough wrought metal at minimum cost for 35 material and labor in assembling the same, and to provide upon the opposite cast member of said frame, sash fastening means cast in unitary relation therewith and at minimum expense.

40 As hereinafter described; the regions of the members which are to be joined together are provided with small projections in groups in such spaced relation that the two members 45 forming the joint may be drawn into and retained in rigid relation by a single screw.

My invention includes the various novel features of construction and arrangement hereinafter more definitely specified.

50 In said drawings; Fig. I is a front eleva-

tion of a cast metal frame, hingedly connected with a wrought metal sash and having fastening means for the latter in unitary relation with the frame.

Fig. II is a rear elevation of said structure 55 shown in Fig. I.

Fig. III is an end elevation of said frame.

Fig. IV is a vertical sectional view of said frame and sash, taken on the line IV, IV in 60 Figs. I, II, and III.

Fig. V is a top plan view of said frame.

Fig. VI is an inverted plan view of said frame.

Fig. VII is a fragmentary inverted plan view of a portion of said upper frame member showing the construction and arrangement of the hinge member. 65

Fig. VIII is a fragmentary vertical sectional view taken on the line VIII, VIII in 70 Figs. II and V, and showing the construction and arrangement of the frame and sash hinge members.

Fig. IX is an end elevation of the top or "lintel" of said frame.

Fig. X is an end elevation of the bottom or "sill" member of said frame, showing the location and arrangement of the group of spacing projections serving as bearings for the vertical members. 75

Fig. XI is an inside elevation of one of the frame jamb members, showing the location and arrangement of the groups of three spacing projections serving as bearings for the horizontal members of the frame. 80

In said figures; the rectangular window frame 1 is conveniently formed of four cast channel bar members; to wit, the lintel member 2, sill member 3, and opposite vertical jamb members 4 and 5. Said members 2 and 3 are respectively differently constructed and arranged, as hereinafter described, but said members 4 and 5 are precisely alike in construction and arrangement, altho disposed in reversed relation. 85

Said lintel 2 has a longitudinal web 7 inclined downwardly from the front to the rear of said frame 1, and has upwardly extending longitudinal flanges 8 and 9 respectively at the front and rear edges thereof, and the downwardly extending longitudinal flange 10 90

intermediate of said flanges 8 and 9, and forming the sash recess 11.

Said lintel 2 has oppositely counterpart flanges 13 and 14 extending vertically at opposite ends thereof between said flanges 8 and 9 and forming recesses 15 and 16 in which the joints are made, as hereinafter described. Said lintel 2 has, at opposite ends thereof, two sockets 18 fitted to receive projections on the jamb members as hereinafter described, and a screw threaded socket 19 between said sockets 18, fitted to hold the cap screws 20. Said lintel member 2 also has pairs of downwardly extending flanges 21 upon the under side thereof in said recess 11 in such spaced relation as to embrace between them the hinge members 22 which, as shown in Fig. VIII, are angle plates of wrought metal which are held between respective pairs of flanges 21 by respective single screws 24.

Said sill member is oppositely counterpart to said lintel member and similarly constructed and arranged, including a longitudinal web 27 having downwardly extending longitudinal flanges 28 and 29 as respectively opposite edges thereof with an upwardly extending longitudinal flange 30 intermediate of said flanges 28 and 29 forming a sash recess 31. However, said sill member differs from said lintel member in that it has no hinge means but has, intermediate of its length, a keeper socket flange 33 forming a wedge-shaped slot 34 for sash fastening means, as hereinafter described.

Said sill member 3 has oppositely counterpart flanges 36 and 37 extending vertically at opposite ends thereof between said flanges 28 and 29 and forming recesses 39 and 40 in which the joints are made, as hereinafter described. Said sill 3 has, at each of the opposite ends thereof, two sockets 41 fitted to receive projections on the jamb members, as hereinafter described, and a screw threaded socket 42 between said sockets 41, fitted to hold the cap screws 44.

Each of said jamb members 4 and 5 (which, as above stated, are precisely alike, but disposed in reversed relation in the frame 1,) has a longitudinal web 46 inclined inwardly, toward the center of the frame, from the front to the rear thereof, and has outwardly extending flanges 47 and 48 respectively at the front and rear edges thereof, and the inwardly extending longitudinal flange 49 intermediate of said flanges 47 and 48 and forming the sash recess 50.

Each of said jamb members 4 and 5 has oppositely counterpart vertically extending flanges 52 at respectively opposite ends thereof, of which flanges are offset outwardly to form recesses 53 for reception of the ends of said lintel 2 and sill 3 and, as shown in Fig. XI, each of said flanges 52 is provided with a hole 54 for engagement with either a screw 20 extending from the lintel 2, or a screw 44

extending from the sill 3. Each of said jamb flanges 52 is also provided with a group of three projections in such spaced relation with respect to said screw holes and screws that the two members forming each joint may be drawn into and retained in rigid relation by a single screw. Each group of projections includes two projections 56 which are preferably circular and conical and adapted to seat in either the sockets 18 on the lintel or the sockets 41 on the sill, and each of said groups includes a third projection 57 which may be a straight rib. Said projections are of such shape that they may be readily cast economically, and such that the members composing each joint may be assembled in rigid relation without planing or otherwise facing or machining said projections or the opposing surface with which they come in contact.

It is to be particularly noted that altho the flanges 49 on the opposite jamb members 4 and 5 extend in the same plane as the flange 10 on the lintel member 2, the flange 30 on the sill member 3 is offset closer to the rear face of the frame 1 and stops short of the opposite ends of the frame, so as to permit drainage of rain water from said jamb flanges 49 to flow down the sill incline and be discharged at the outer face of the frame 1. If such a weathering arrangement of the flanges 30 and 49 were not provided, the rain water aforesaid would be trapped and tend to flow down into the sash recess 31.

The sash 60 is conveniently formed of sections of wrought metal bars respectively forming the top rail 61, bottom rail 62, opposite end stiles 63, and mullions 65, all of which are welded together in rigid relation and form a plane flange 66 which is continuous around said sash and adapted to fit against the rear plane face of said window frame 1. The flange 66 on said top rail 61 has slots 67 to receive said hinge plates 22. The bars 68 above said slots are offset rearwardly so that they form pivotal connections with said hinge plates 22; so that said sash 60 may be freely swung rearwardly without interference of its top flange 66 by contact with said window frame 1. It may be observed that the construction and arrangement are such that when said sash is raised until its bottom edge is slightly above the plane of said hinge plates, the sash may be unhooked from said plates and removed. Said sash members 61, 62, and 63 are of the same cross-section, which is substantially L-shaped, but has an inwardly turned glass retaining flange 70 at the outer edge thereof and in line with the flanges 71 on said mullions 65 which are of T-shaped cross-section, so that the sash is adapted to hold three panes of glass 73 which are retained therein by fillets of cement 74.

Said sash 60 has fastening means including the lever latch 76 which is connected

therewith by the rivet pivot 77 so that its arm 78 may be turned downwardly into the wedge-shaped slot 34 in the socket 33 on the window sill member 3 to press said sash flange 66 against the rear face of said window frame 1.

I find it convenient to provide said sash 60 with a weathering member at the bottom thereof comprising the channel bar 79 which is rigidly connected with the bottom rail 62 of said sash, conveniently by spot welding the same. As indicated in Fig. IV, said channel bar 79 fits in the sash recess 31 in the sill member 3 of the window frame 1 in close relation therewith, and the double flanges on said bar 79 serve to check the flow of any moisture inward with respect to said frame and thus prevent the same from dripping over the inner face of the subjacent wall.

I also find it convenient to extend said flanges 48 on the jamb members 4 and 5 of the sash frame 1 so that they overlap the wooden or masonry setting in which said frame is placed, and said flanges may be provided with holes 81 for means such as nails or screws for rigidly securing said frame in said setting. However, if the setting is masonry, said frame 1 may be otherwise secured, for instance, by flowing mortar or other cementitious material into the recesses exterior to the inclined web flanges 7, 27, and 46 on the respective frame members 2, 3, 4, and 5.

Altho I have described an embodiment of my invention in a position in which it may be employed as a cellar window, of course, it may be otherwise positioned, for instance, either of what I have termed the jamb members 4 and 5 may be the top or bottom of the frame, in which case the sash would be hung on a vertical axis and, of course, other forms of sashes may be used in connection with window frames constructed in accordance with my invention.

Altho the sockets 18 on the lintel and the similar sockets 41 on the sill are useful in that they laterally engage the projections 56 and prevent relative displacement of the frame members at the joints thus engaged even if the screw 20 or the screw 44 be omitted at such joint; such frame members as above described may be held together in rigid relation by a single screw at each joint without the provision of any such sockets; the group of three projections 56 and 57 surrounding such screws being drawn into stable relation with the opposing member, by the single screw local to said projections.

Therefore, I do not desire to limit myself to the precise details of construction and arrangement herein set forth, as it is obvious that various modifications may be made therein without departing from the essential features of my invention, as defined in the appended claims.

I claim:

1. A cast metal window frame comprising four channel bar members, each having a screw opening at each end thereof, the screw openings in adjoining ends of said members being in registry with each other, and one of said members, at each of said joints, having a group of bearing projections in spaced relation around such screw opening therein and adapted to bear upon the other member at said joint and be held in rigid relation spaced therewith by a single screw, and single screws extending in registered screw openings at each joint and clamping said frame members in rigid relation whereby said joints may be made between unfinished surfaces of said members, which are held in spaced relation with each other by said screws.

2. A window frame structure as in claim 1; wherein each group of bearing projections is limited to three.

3. A window frame structure as in claim 1; wherein the frame member opposed to the frame member having projections, has sockets cast therein and fitted to receive such projections; whereby said frame members may be prevented from lateral displacement if and when any one such screw is removed.

4. A cast metal window frame comprising four channel bar members, each having but one screw opening at each end thereof, the single screw openings in adjoining ends of said members being in registry with each other and intermediate of spaced bearing projections, and single screws extending in registered screw openings at each corner of said frame and clamping said frame members in rigid rectangular relation at unfinished regions thereof.

5. A window frame structure; wherein one of the frame members has pairs of hinge retaining flanges thereon with single screw openings in between said flanges; hinge members comprising respective hook plates, each having a single screw opening and respectively adapted to fit between said pairs of hinge retaining flanges; and single screws respectively rigidly connecting said hinge plates to said frame member, whereby portions of said hinge members serve as pintle seats in axial alinement; a sash comprising a metallic flange having slots extending longitudinally therein at one edge thereof and bars formed of the metal between said slots and the edge of said sash, which bars are offset with respect to the plane of the sash and serve as axially alined pintles, adapted to be detachably engaged in the hinge members of said window frame; whereby said sash may be detachably hingedly engaged with said frame.

6. A window frame structure wherein one frame member is provided with hinge members and an opposite frame member has cast

in unitary relation therewith a sash retaining socket forming a slot which is wedge-shaped; and a sash hingedly hung on said frame hinge members and having a pivoted latch adapted to be turned into said slot to tightly clamp 5 said sash against said frame.

7. A window frame structure wherein one of said frame members forms a sill and each of said members has an inwardly extending 10 flange forming a sash recess; the flange forming the sash recess on said sill being offset inwardly with respect to the front of said frame; whereby moisture draining from the side members of said frame may drain outwardly over said sill from in front of said 15 sill flange.

8. A cast metal window frame comprising four channel bar members; each of said frame members having a web flange extending longitudinally therein and inclined from front to rear thereof; whereby the opening of said frame is larger at the front than at the rear; sash stop flanges extending longitudinally on each of said three frame members; said stop 20 flanges on three of said members being in alinement in the same plane, and the sash stop flange on the fourth member of said frame being offset from the plane of the other stop flanges and toward the rear thereof; 25 whereby moisture draining from said three alined flanges is free to escape in front of the offset stop flange to drain away from said flange.

9. A cast metal window frame member having, near one end thereof, a screw hole and a 30 group of bearing projections in spaced relation around said hole and terminating in planes parallel with the plane of said member; whereby an unfinished surface of said member is adapted to be joined in rigid spaced 40 relation with an unfinished surface of another frame member by a single screw extending in said hole and clamping said frame members in rigid spaced relation at said unfinished 45 surfaces.

10. A window frame member as in claim 9, having end portions extending in a common plane but offset outwardly with respect to the plane of the other portion of said member, and having a screw opening and a group 50 of bearing projections around such opening at each of said offset portions; whereby said member is adapted to be held in rigid relation with two other frame members respectively connected therewith by single screws 55 extending in said openings.

11. A window frame member as in claim 9; wherein the group of bearing projections includes two which are conical.

12. A cast metal window frame member 60 having at one edge thereof pairs of flanges, in spaced relation, each of said pair of flanges having an intermediate opening for hinge fastening means; and hinge members adapted 65 to fit between said flanges entirely at one sur-

face of said member and having respective holes adapted to register with the holes in said frame member; and fastening means extending thru the registered holes in said frame and hinge members, and rigidly connecting the latter with said frame member. 70

13. A cast metal window frame member having at one edge thereof, and in unitary relation therewith, a flange forming a wedge-shaped slot, tapered longitudinally with respect to said member, for engagement with sash retaining means. 75

14. A cast metal window frame comprising four channel bar members, each having a screw opening at each end thereof, screw openings in adjoining ends of said members being in registry with each other; two of said members having end portions which are offset outwardly; two of said members having end portions which are offset inwardly; whereby said frame members are adapted to fit together in interlocked relation with said screw openings in registry at the respective corners of said frame; and screw means extending thru the registered openings in said frame members and clamping them in rigid relation. 80

15. A window frame structure as in claim 14; wherein each of the frame members has opposite longitudinal flanges with a recess 85 between them presented outwardly, and adapted to receive and hold cementitious material between said frame and a masonry setting; whereby said frame may be held in interlocked relation with such setting. 90

16. A window frame structure as in claim 14; wherein each of the frame members has longitudinal flanges extending outwardly respectively parallel with the plane of said frame; and said flanges, at opposite sides of the frame, have openings for fastening means; whereby said frame may be secured in rigid relation with a building wall in which it is set. 105

17. A cast metal window frame member having end portions which are offset inwardly; whereby said member is adapted to fit in interlocked relation with two other members at said offset portions. 110

In testimony whereof, I have hereunto signed my name at Norristown, Pennsylvania, this twenty-seventh day of September, 1929.

CHARLES GABRIEL O'HARA.
